UNITED STATES PATENT OFFICE.

WILLIS A. CALKINS, OF ABINGTON, MASSACHUSETTS, ASSIGNOR TO KAKAS BROS., INC., OF BOSTON, MASSACHUSETTS, A CORPORATION OF MASSACHUSETTS,

STRETCHING FRAME.

Application filed January 17, 1925. Serial No. 3,039.

My invention relates to a device for holding or stretching skins or pelts for drying, curing, or otherwise treating the same.

My invention will be best understood from the following description when read in light of the accompanying drawing of a specific embodiment of my invention selected for illustrative purposes, while the scope of my invention will be more particularly pointed out in the appended claims.

In the drawing:—

Fig. 1 is an elevation of a device constructed according to my invention;

Fig. 2 is a side view according to Fig. 1;

Fig. 3 is a section on the line 3—3 of Fig. 1; and

Figs. 4 and 5 are respectively sections on the lines 4—4 and 5—5 of Fig. 3.

Referring to the drawing and to the preferred embodiment of my invention I have shown a V-shaped frame which conveniently is made of a resilient rod bent to form the opposite side arms 1 and 3, which arms are movable toward and away from each other about the portion 5 forming the apex of the frame. For limiting the extent of separation of the side arms the side arm 3 at its lower end is bent at right angles to form a side arm connecting portion 7 which extends through an eye 9 formed at the end of the side arm 1, the outer end of the portion 7 being bent upwardly to form a stop 11 coacting with the eye 9.

For holding the side arms 1 and 3 apart and for providing a means to which the lower end of the skin or pelt may be attached when the frame is in use I provide a cross bar 13 conveniently made of a length of flat bar stock which at opposite ends has formed therein slots 15 through which the side arms 1 and 3 extend. At each end the cross bar has pivoted thereto at 17 the end of a side arm engaging member 19, each member 19 being formed on one side thereof with notches 21 adapted to engage the adjacent side arm. As indicated in Fig. 1 the side arms 1 and 3 on their inner edges are formed with a series of spaced notches 23 which engage the sides of the notches 21 of the members 19 for holding the cross bar in adjusted position lengthwise of the side arms.

For gripping the skin or pelt to the cross bar I provide a bar 25 which as shown is of the same thickness as the stock forming the

cross bar. The bar 25 adjacent one end is connected to the bar 13 by means of the links 27 which at opposite ends are pivoted at 29 and 31 to the bar 25 and bar 13 respectively, the length of the links being such as to normally space the opposed edges of the bars slightly apart. At its end opposite the links 27 the bar 25 is formed to provide an inclined series of notches 31 with which notches cooperates a catch 33 in the form of a bail pivoted at 35 to the bar 13, by means of which construction skins or pelts of different thicknesses may be gripped between the bars 13 and 25. For insuring the gripping action the adjacent edges of the bars 13 and 25 respectively are formed with recesses 37 and cooperating teeth 39.

Although I have described for purposes of illustration one specific embodiment of my invention it is to be understood that I am not limited thereby to its particular mechanical details, but that within the scope of my invention wide deviations may be made therefrom without departing from the spirit of my invention.

Claims:

1. A skin stretching frame comprising in combination, a pair of side arms movable relatively to each other, a cross bar slidable along said arms and carrying means for holding said arms apart, a flat bar pivotally connected at one end by a link to said cross bar and arranged with one edge thereof presented to an edge of said cross bar and slightly spaced therefrom, teeth projecting from one of said edges and cooperating indentations formed in the other of said edges, said bar pivoted to said cross bar having at one end thereof an inclined series of notches, and a catch for engaging said notches pivotally connected to said cross bar.

2. A skin stretching frame comprising in combination, a pair of side arms movable relatively to each other, a cross bar slidable along said arms and carrying means for holding said arms apart, a skin gripping means comprising a flat bar carried by and movable relatively to said cross bar and arranged with one edge thereof presented to an edge of said cross bar, and said flat bar having its opposite edge at one end formed with an inclined series of notches, and a catch carried by and movable relatively to said cross bar cooperating with said notches.

3. A skin stretching frame comprising in

- combination, a pair of side arms movable relatively to each other, a cross bar slidable along said arms and carrying means for holding said arms apart, a skin gripping means comprising a flat bar carried by and movable relatively to said cross bar and arranged with one edge thereof presented to an edge of said cross bar, cooperating teeth formed on said edges, and said flat bar having its opposite edge at one end formed with an inclined series of notches, and a catch carried by and movable relatively to said cross bar cooperating with said notches.
4. A skin stretching frame comprising in combination, a pair of side arms movable relatively to each other, a cross bar slidable along said arms and carrying means for holding said arms apart, means carried by said cross bar for gripping a skin, said means comprising a member cooperating with said cross bar for engaging a skin between them, said member attached adjacent one end thereof to said cross bar for movement toward and from said cross bar, said member adjacent its opposite end formed with a series of notches, said series being inclined relative to said member and cross bar
- to place the notches nearest the end of said member nearer the cross bar than those notches farthest from said end, and a catch 30 movably carried by said cross bar for selectively engaging said notches.
5. A skin stretching frame comprising in combination, a pair of side arms movable relatively to each other, a cross bar member 35 slidable along said arms, skin gripping means comprising a second member cooperating with said cross bar member for gripping a skin between said members, said second member being pivotally attached to said cross bar, and means for holding said members in gripping relation comprising a catch on one of said members and a series of catch engaging means on the other, said series being inclined relative to said members to place those catch engaging means farthest from the point of attachment of said members nearer said cross bar than those catch engaging means nearest said point of attachment.

In testimony whereof, I have signed my name to this specification.

WILLIS A. CALKINS.
